(57) **CLAIM**

The ornamental design for a cutting tool, as shown and described.

DESCRIPTION

FIG. 1 is a top front perspective view of a cutting tool showing my new design;

FIG. 2 is a bottom rear perspective view thereof;

FIG. 3 is a front elevational view thereof;

FIG. 4 is a back elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a top front perspective view thereof, wherein a chainsaw attachment is shown connected to the cutting tool;

FIG. 10 is a top front perspective view thereof, wherein a circular saw attachment is shown connected to the cutting tool; and,

FIG. 11 is a top front perspective view thereof, wherein a reciprocating saw attachment is shown connected to the cutting tool.

The broken lines showing switches and buttons in FIG. 1-11, the broken lines showing recessions and protrusions in FIG. 1-11, the broken lines showing a chainsaw attachment in FIG. 9, the broken lines showing a circular saw attachment in FIG. 10, and the broken lines showing a reciprocating saw attachment in FIG. 11 are included for the purpose of illustrating environmental structure and form no part of the claimed design.
